UNITED STATES PATENT OFFICE.

ALAIN SAINT OGAN, OF PARIS, FRANCE, ASSIGNOR TO LOUIS DANGEL.

DESIGN FOR A STATUETTE OR SIMILAR ARTICLE.

Application filed May 21, 1928. Serial No. 28,774. Term of patent 7 years.

To all whom it may concern:

Be it known that I, ALAIN SAINT OGAN, a citizen of France, residing at Paris, France, have invented a new, original, and ornamental Design for a Statuette or Similar Article, of which the following is a specification, reference being had to the accompanying drawing, forming part thereof.

Fig. 1 is a side view of a statuette embodying the new design;

Fig. 2 is a front view of the statuette; and Fig. 3 is a side view looking from the direction opposite to that from which the statuette is viewed in Fig. 1.

I claim:

The ornamental design for a statuette or similar article, as shown.

ALAIN SAINT OGAN.
